MACHINE FOR MAKING MILK BOTTLE CAPS

Peter W. Ryser, Portland, Oreg.

Application May 27, 1940, Serial No. 337,469

3 Claims. (Cl. 93—1.3)

My invention relates to improvements in machines for the manufacture of milk bottle caps, the caps to be made by my machine being of the so-called disk type made from fibrous materials, having a pulling tab associated therewith for removing the cap from the milk bottle, with the base end of the tab being stapled to the body of the cap to prevent its being torn from the cap.

In the production of the cap the final operation is that of coating the same with a suitable wax, as paraffin, and finally passing the same within the container.

My invention is comprised primarily of a frame, the top portion of which is hinged at one end and is adapted for being raised and lowered. The roll of paper from which the caps are to be made is rotatably supported at one end of the frame, and the strip of paper is pushed into the machine by feeding rolls at one end, and the final strip of punched paper is pulled from the machine at its opposite end.

The initial stage of operation consists in feeding the strip of paper to the position where the cap is to be punched then printing the cap where the punch is to be made to form the cap but in advance of punching the same, then progressively forming the tab upon the printed face of the cap to be punched; then stapling the base end of the tab; then cutting the cap from the sheet by punching; then conveying the caps through the wax for coating the same, and finally cooling and delivering the caps into a receiving container.

The primary purpose and object of my invention is to produce a simply constructed device for the purpose intended; one that will be rugged in construction and one that will have a long and useful life, with practical freedom from mechanical operating annoyances.

A still further object of my invention is to so construct my device that it will have a minimum first cost.

A still further object of my invention is to so construct the device through the operation of which the dairyman and small milk distributor may make his own caps with workmen commonly employed by dairies and milk distributing plants.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. I is a fragmentary side view, partially in section of the assembled device.

Fig. II is a fragmentary sectional end view of the assembled device.

Fig. III is a fragmentary sectional end view of the device, taken along the line III—III of Fig. I.

Fig. IV is a fragmentary plan view of a strip from which milk bottle caps are to be made, from which milk caps have been punched and in which the pulling tab has been made and stapled but in which the cap has not been punched.

Fig. V is a fragmentary side view of the assembled device. This view is of the inking rolls and the printing pads utilized for printing the caps to be formed. This view is taken on line V—V of Fig. II.

Fig. VI is a fragmentary plan view of the immersing tank, the cooling chute, and the elevating rolls utilized in off-bearing and delivering the finished caps into a shipping tube.

Fig. VII is a sectional end view of the mechanism illustrated in Fig. VI. This view is taken on line VII—VII of Fig. VI.

Fig. VIII is a perspective plan view of the milk bottle cap that is formed by my machine.

Like reference characters refer to like parts throughout the several views.

I form my machine of a suitable fabricated bed 1, and I support the bed upon pairs of legs 2 and 3 that are disposed at the opposite ends of the bed.

A supporting frame 4 is provided. The frame 4 is in hinged relationship with the bed 1. This is accomplished by supporting a shaft 5 within suitable journalled bearings disposed respectively within the bed 1 and within the frame 4.

Milk bottle caps are made from strip material.

6. The strip material generally comes in rolls, and I have here shown the strip 6 as being unwound from a roll 7. The roll 7 is supported upon a shaft 8, and the shaft 8 is mounted upon any suitable stand 9.

In order that due compensation may be made for the decreasing of the diameter of the roll 7 as the paper strip is drawn therefrom, I provide a pair of arms 10 that are suitably supported upon the legs 3, and I mount a roller 11 within the upper end of the arms 10. The top of the roller 11 is in registry with the under side of the strip and in registry alignment with the strip as it passes through the machine.

A pair of feeding rollers, not here shown, are mounted within a suitable frame 12. The top roller is mounted within an adjustable block 13,

and the top roller is made to engage the top of the strip of paper.

The bottom roller is mounted upon a shaft 14, and the shaft 14 is journaled within the frame 12, with the frame 12 being supported upon the feeding end of the bed 1.

An arm 15 is mounted upon the shaft 14, and a ratchet wheel 16 is fixedly secured to the shaft 14. A ratchet pawl 17 is carried by the arm 15. The ratchet pawl 17 is hingedly secured to the arm 15, and the movable end of the pawl is made to ride upon and engage the toothed surface of the ratchet wheel 16.

A bracket 18 is also secured to the arm 15, and a spring 19 is disposed between the bracket 18 and the pawl 17 and normally maintains contact between the pawl and the ratchet wheel.

Suitable feeding pressure is developed between the respective feeding rolls through the action of a pressure adjusting hand screw 20. A table 21 is disposed beneath the bed 1, and the table 21 is supported at one end by the legs 3. It is suspended from the bed by its opposite end by a suspension member 22.

Connecting rods 23 are provided for imparting an up and down movement to the frame 4. A floating journal block 24 is mounted within the upper end of the connecting rod 23, and a shaft 25 is mounted within the floating block 24. The floating block 24 is positioned within the connecting rod 23 by a hand adjusting screw 26. The shaft 25 is positioned relative to the table 4 by a journal block 27.

A compression spring 109 is disposed within the line of travel and in contact on its respective ends with the floating journal blocks 24, and the amount of compression within the spring is determined through the hand adjusting screw 26.

I place an electric switch 110 in registry with the adjusting screw 26, and in the event of any foreign matter being placed between the printing heads 68 and the platen 67 or between the tab forming dies 69 and 70 and the anvil block 71, or between the respective punches 76, 77, 78, and 79 and the die block 75, the plunger 111 of the switch 110 will be made to contact the screw 26, which will throw the switch and therefore stop the motor, because the switch 110 is disposed within the same electric circuit that supplies energy to the prime mover 28.

A prime mover, as an electric motor 28, is mounted upon a table 21, and a driving pulley 29 is disposed upon the armature shaft of the prime mover.

A shaft 30 is journaled within a bracket 31 mounted upon the table 21, and a pulley 32 is disposed upon the shaft 30. Driving relationship is effected between the pulleys 29 and 32 by a belt 33.

A pinion 34 is mounted upon the shaft 30, and a master gear 35 coacts with and is driven by the pinion 34. The gear 35 is secured to a crank shaft 36. The shaft 36 is journaled within any suitable support 37 that rests upon the table 21.

The connecting rods 23 and 23a are two in number, and they are secured to the crank arms 38 and 39 respectively that are disposed at the opposite ends of the shaft 36, so that as the crank gear 35 is rotated the crank shaft 36 will also be rotated and an up and down movement will be imparted to the connecting rods 23 and 23a.

A pitman rod 40 is hingedly connected on its one end to the arm 15 and upon its opposite end to a block 41. The connecting rod 23 has a slot 42 disposed therein, and the block 41 is adjust-

able along the slot 42 by an adjusting hand set screw 43.

As the crank shaft 36 is rotated, a pendulum-like action is imparted to the connecting rods 23 and 23a, and simultaneously therewith an up and down movement is imparted to the connecting rods 23 and 23a. Because of this movement of the connecting rods 23, a longitudinal movement is imparted to the pitman rod 40, and because of this movement the ratchet wheel 16 and the shaft 14 are partially rotated; consequently the feeding roll disposed upon the shaft 14 is also rotated to feed the strip of paper 6 for the space required for one milk bottle cap at each rotation of the crank shaft 36, and likewise an up and down movement is also imparted to the swinging end of the table 4.

In the production of milk bottle caps through the use of my machine, I initially print the cap before the forming of the pulling tab or the stapling of the same at the base end of the tab. I accomplish this by placing printing heads upon the plungers, here shown as four in number, in Fig. II at 68. These plungers are carried by a support 47A that is fixedly secured to the frame 4.

Inking rollers 48 and 49 are provided for inking the printing heads 68 in advance of each printing operation. The inking rollers are carried on the lower end of the movable arm 50, and the movable arm 50 is hinged at its upper end about a hinged pin 51.

Guide bars 52 are provided. These guide bars 52 determine the path of movement of the ink rollers 48 and 49, and a coil spring 53 that is secured upon its one end to the movable arm 50 and upon its opposite end to the bifurcated head 54. The purpose of the spring is to urge the inking rollers into contact and out of contact with the printing heads, the same being so timed as to move and ink the printing heads in timed relationship with the printing operation, so that at each printing operation the rollers are passed over the printing heads twice for each printing operation.

A connecting rod 55 is provided for moving the inking rollers and the inking instrumentalities associated therewith. The connecting rod is hingedly secured to the bifurcated head 54 by a hinged pin 57, and the bifurcated head 57 is rockably supported upon a shaft 58.

A fountain 59 is provided for the ink, and the ink rollers 48 and 49 are replenished by contacting the same with an ink supplying drum 60, or other inking instrumentality that is associated with the fountain of the conventional type not here shown, the ink supplying drum 60 being placed in the line of travel of the ink rollers, and over which the same passes at each printing cycle.

The shaft 61 about which the inking roller 60 is disposed has an arm 62 disposed thereupon, and a ratchet wheel 60a is secured to the shaft 61; with a feeding pawl coacting with and partially rotating the ratchet wheel 60a at each movement of the arm 62.

The feeding pawl 63 is supported upon a shaft 64. An arm 65 is secured to the shaft 58, and as the shaft 58 is rotated through the movement of the bifurcated head 54 a pendulum-like action is imparted to the arm 65.

A connecting rod 66 connects the respective arms 62 and 65, to impart a feeding action to the feeding pawl 63. The strip 6 is drawn over a suitable platen block 67. If more than one color is to be printed upon the cap to be formed, additional printing heads, as shown at 68, are pro-

vided, which may be inked as heretofore described.

In order to provide for more than one color of inking, the ink rollers may be deeply grooved between their ends in order that the different colored inks may be confined to the surfaces of the roller between the end and the split portion.

In milk bottle caps of the disk type, it is necessary to provide a pulling tab upon the top side of the cap. I accomplish this through the use of tab-forming dies 69 and 70. The dies 69 and 70 are removably secured to the under side of the frame 4 and the printed strip from which the caps are to be made is pulled over any suitable anvil block 71. The dies 69 and 70 are positioned and arranged to score the cap at the location and in the form of the tab, but to not entirely cut through the material from which the cap is made. After the tab is scored along the line of the staple 74 and slit around that portion of the edge of the tab that is to be pulled upward from the body of the cap after the cap has been applied to the bottle, it is then necessary to staple the seared tab 72 adjacent its base end, as illustrated to prevent the pulling of the tab from the cap. The tab is of the conventional type formed on milk bottle caps and no special claim is made therefor. The tab is pulled up when the cap is to be removed from the milk bottle.

A stapling machine 73 is mounted within the frame 4, and at each cycle of operation of the frame 4 the stapling machine is actuated to force a wire staple 74 through the cap and to staple the cap 112 at the base of the tab 72.

The strip of paper is drawn through the stapling machine and between the base of the machine, and the staples in order to facilitate the same being forced through the strip of paper. After the milk bottle caps have been printed the tabs are formed thereupon, and the same are stapled to the cap; it is then finally released to shear the cap from the strip.

I place a die block 75 in registry with and immediately below the punches, here shown as four in number at 76, 77, 78, and 79, with the die block having a hole 80 disposed therein for each of the respective punches, with each of said holes being placed immediately below and in registry with the punch disposed thereabove.

It may be found desirable to place the respective punches out of registry with each other transversely of the machine in order to lessen the blow created by the punching of the cap from the stock of strip material. See arrangement in Fig. VI.

Heretofore it has been the general custom to form milk bottle caps from waxed paper stock. The wax coating in many instances prevents the printing being satisfactory, did not completely coat the paper, and in addition thereto necessitated the use of a greater amount of wax because the entire surface of the strip was coated.

The punched caps 112 in my operation are deposited within a vat 81. The vat 81 is filled with coating wax, and the temperature of the wax is maintained at proper working viscosity by the placing of an electric heat element 82 within or without the vat, and the temperature may be automatically maintained by placing a thermostat 83 within the vat 81, with the thermostat 83 being placed within the electric circuit for supplying electric energy to the electric heater 82.

An endless conveying belt 84 is operated within the vat and is power driven to convey the punched caps 112 from the vat; in order to insure complete immersion within the wax a dunking roller

85 rides the top of the endless conveying belt 84, which requires all caps 112 to pass between the dunking roller 85 and the top side of the belt, which insures a complete immersion of all caps passing through the vat.

The endless conveying belt 84 also conveys the caps 112 from the vat and delivers the same into a discharge cooling chute 86.

The completed coated caps 112 are deposited within the cooling chute, and I provide a suction through the chute 86 by connecting a tube 87 to a source of suction not here shown.

In the event that normal air does not cool or solidify the wax sufficiently rapid that is disposed upon the outer surface of the caps, the same may be suitably cooled or refrigerated by any of the well known refrigerating means, as by drawing the air entering the tube 86 through a refrigerated box 88 that may be filled with ice or with coils through which a refrigerant is circulated.

The endless belt 84 is driven by a prime mover 89. The prime mover 89 is supported upon any suitable bracket support 90. A bevel gear 91 is mounted upon the armature shaft of the prime mover, and the gear 91 coacts with and drives the gear 92.

The gear 92 is mounted upon a shaft 93, and a bevel gear 94 is also mounted upon the shaft 93, and the same coacts with and drives a bevel gear 95 that is mounted upon the shaft 96.

Suitable drums or sprockets 97 and 98 are disposed upon the shafts 96, and 99, to thereby drive the endless conveying belt 84.

Milk bottle caps are generally delivered to the ultimate consumer in tubes, and I automatically place the caps in position for being delivered into tubes by placing a pair of coacting worm gears 100 and 101, with the gears being placed in registry with the discharge end 102 of the chute 86.

The finished caps are fed by the worm gears 100 and 101 and are delivered into a filler tube 103. The filler tube is inclined from the horizontal upward to insure contact of the caps within the tube, and a tube to be filled is inserted within the bell-shaped end 104 of the tube 103.

The respective worms 100 and 101 are driven by beveled gears 105 and 106, and coacting spur gears are mounted upon the outer ends of each of the worm gears to drive the same, as illustrated at 107.

Upon the filling of the tube 108 with the required number of caps, the same is removed from the filler tube and an additional one is added thereto.

While the form of mechanism herein shown and described is admirably adapted to fulfill the objects primarily stated, it is to be understood that it is not intended to confine the invention to the embodiment herein shown and described, as it is susceptible of embodiment in various forms, all coming within the scope of the claims which follow.

What I claim is:

1. A milk bottle cap machine comprised of a bed, legs disposed at the opposite ends of the bed, a frame superposed the bed extending longitudinally of the bed and hinged relative thereto, printing heads, tab forming heads, and punches secured to the frame downwardly extending therefrom, and a platen block disposed below the printing heads, an anvil disposed below the tab forming heads, and a die block disposed below the punches, with the lower end of the printing heads, the tab forming heads, and the punches

being in normal spaced relation with the platen, the anvil block, and the die block disposed therebelow, means for intermittently progressing a strip of paper to be made into caps over the platen block, the anvil, and the die block, and means for imparting an up and down movement to the swinging end of the frame.

2. A machine of the class described consisting of a stationary frame, a hinged frame mounted over said stationary frame, said hinged frame having attached thereto printing heads, tab forming punches, stapling punches and cap severing punches in series, and a conveyor for moving a paper web past all of said units while said hinged frame is in an uppermost position.

3. A machine of the class described consisting of a stationary bed, a vertically movable frame disposed over said bed, means for drawing a paper web between said bed and frame, a printing unit carried by said frame adapted to print milk bottle caps on said web while resting on said bed, a tab outlining punch carried by said frame for partially severing a tab within the boundary of the printed cap, a stapling unit for placing staples across one end of each tab and a punching unit attached to said frame for severing the caps from the web.

PETER W. RYSER.
